UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

FEED MECHANISM.

1,105,343

Specification of Letters Patent.

Patented July 28, 1914.

Application filed February 14, 1913. Serial No. 748,367.

To all whom it may concern:

Be it known that I, RICHARD LESTER WILCOX, a citizen of the United States, residing at Waterbury, in the county of New Haven 5 and State of Connecticut, have invented certain new and useful Improvements in Feed Mechanism, of which the following is a specification, reference being had therein to the accompanying drawings.

10 My invention relates to a new and improved feed mechanism, of that type wherein a blank is carried from a delivery position to a point where it is received by, and operated upon, by one or more tools. It is 15 shown and described herein as applied to a bolt trimming machine, wherein the round heads of blanks are trimmed so as to make them square, hexagon, or any other desired shape, as well as to trim off the flash from 20 the underside of the heads of hot forged bolts. It is not limited, however, to such use.

It is the object of my invention, among 25 other things, to provide mechanism to perform the operation briefly described above, that will take blanks from the so-called delivery position and move them in a path at substantially a right angle to that through which they traveled to arrive at said delivery 30 position, as desired, that will be composed of few parts, so designed that they may be constructed and assembled at the minimum cost, and be positive in their operation so long as nothing abnormal interferes with the continuous and smooth 35 running thereof, but will yield as soon as any of the parts meet with an obstruction, thereby preventing the breakage thereof.

To these, and other ends, my invention 40 consists in the feed mechanism, having certain details of construction and combinations of parts, as will be hereinafter described and more particularly pointed out in the claims.

45 Referring to the drawings, in which like numerals of reference designate like parts in the several figures; Figure 1 is a plan view of my improved mechanism as attached to a bolt trimmer; Fig. 2 is a side elevation thereof; Fig. 3 is an enlarged plan view of the transfer mechanism and the parts adjacent thereto; Fig. 4 is a sectional view of the parts shown in Fig. 3, upon line A—B; Fig. 5 is an elevation of the transfer mechanism

with the parts adjacent thereto; Fig. 6 is a 55 sectional view of the die, die block, and adjacent mechanism, taken upon line C—D of Fig. 3; Fig. 7 is a sectional view of the cams and cam sleeve, taken upon line E—F of Fig. 2; Fig. 8 is an elevation of the rock 60 arms; Fig. 9 is a view of the transfer and turn over cams; Fig. 10 is a side elevation of the delivery end of the chute; Fig. 11 is a plan view thereof, with the cover removed; and Figs. 12 and 13 are views of a modified 65 form of die block, with means connected therewith for adjusting the position of the die.

The details of construction and operation 70 of the bolt trimming machine to which my device is applied are well known and in accordance with common practice, and therefore will not be described at length herein, and only referred to when necessary to more completely describe my improvements.

75 As shown in the drawings, the trimming machine comprises a bed 1 supported upon suitable legs 2, having a crank shaft 3 rotatably mounted therein and driven through a pulley 4 fixed thereto, with a gate 5, carrying a punch 7, slidably mounted in the bed and connected with the crank shaft by a pitman 6.

80 The hopper, from which the blanks are delivered, is not illustrated, as any one of the many forms of hoppers, well known in the art, with the connecting delivery chute, may be used. I have, however, shown herein a portion of one type of delivery chute, 85 which comprises the side plates 8 and 9, 90 that are secured to the bed by the brackets 10 and 11, so as to leave an open space 12 therebetween for the blanks to pass therethrough on their way from the hopper, angle plate 13 fixed to the plate 9, which extends 95 across the open space 12 and terminates opposite the end of the side plate 8, and the retaining plugs 14 mounted in the angle plate 13 with their inner ends projecting 100 from the inside thereof, and normally held in such position by the springs 15. The plate 8 is slightly shorter than the plate 9 and the open space 16 between the end thereof and the angle plate 13 is substantially the same in width as the space 12.

105 Attached to the outside of the plate 8 is a reversible block 17, having the recesses 18 and 19 in the opposite ends thereof. In the

drawings this block is shown in the position wherein it is arranged for blanks with long shanks, the recess 19 therein being of greater width than that of the recess 18 and hence 5 will permit the passage therethrough of gripping fingers of greater width than when the block is reversed and the recess 18 occupying the present position of recess 19.

Above the plates 8 and 9 is a cover 20, 10 having a stop block 21 secured to the inner end thereof, the lip 84 on-said block being in the path of the head of the blank and in contact therewith when the shank of the blank engages the inner face of the angle 15 plate 13, as shown in Fig. 10, the blank being shown therein by broken lines.

Rotatably journaled in the box 22 upon one side of the bed 1, is the sleeve 23, having a gear 24 integral therewith at one end and 20 a collar 25, with a stop lug 26 thereon, at the other end, the said gear and collar preventing endwise movement of the sleeve within its journal bearing. Slidably mounted within the sleeve is the spindle 27, 25 having a head block 28 secured to one end thereof and a grooved sleeve 29 threaded upon its opposite end and held in its adjusted positions by the check nut 30. The head block 28 and spindle 27 are held 30 against rotation independently of the sleeve 23 by the guide pin 31, which is secured to the head block 28 by the nut 32. In the outer end of the head block 28 is a slot 33, within which the finger block 34 is secured 35 by the bolt 35. Upon both sides of the finger block 34 are the fingers 36 that are secured to said finger block by the bolt 37 and provided with tips 38 thereon that project inwardly from the end of the finger 40 block 34 toward each other, leaving an open space therebetween, which is opposite the notch 39 in the end of the finger block. The finger tips contact with a new blank in the open space between the ends thereof, and 45 the fingers are forced apart until they have passed over the shank of the bolt, when they spring inwardly to the positions shown in Fig. 4, with the shank of the bolt in the notch 39, and held there against accidental 50 disengagement by the said finger tips.

Endwise movement is imparted to the spindle 27 and the parts connected therewith from the transfer cam 40, through the rock arm 41 that is pivotally mounted upon 55 a stud 42 fixed in the bed 1, and having a cam roll 43 thereon, a crank arm 45 pivotally mounted upon a stud 46 in a bracket 47 fixed to the bed 1, an adjustable connection 44 connecting said rock arm 41 and crank 60 arm 45, blocks 48 mounted in the yoke end 49 of the crank arm 45 that enter the groove in the sleeve 29, and a spring 50 between the crank arm 45 and a pin 51 fixed in the bed, that normally holds the cam roll 43 in 65 contact with the transfer cam 40. This

spring provides a yielding member for the movement of the fingers toward the punch and die, while their movement in the opposite direction is positive, so that if in transferring a blank to the punch and die any part should become clogged, or for any reason the mechanism does not operate smoothly and in the usual manner, the movement of the finger mechanism is stopped, thereby preventing breakage of any of the 70 parts. A rotary movement is imparted to the sleeve 23 from a turn-over cam 52, through a rock arm 53, rotatably mounted upon the stud 42, having a cam roll 54 connected therewith, a sector 55, rotatably mounted upon a stud 56, fixed in the bed 1, having teeth upon the outer edge thereof, which mesh with the teeth in the gear 24; an adjustable connection 57 joining the rock arm 53 with the sector 55, and a spring 58 80 between the sector and the pin 59 fixed in the bed 1, the said spring normally holding the cam roll 54 in contact with the cam 52. Both the transfer cam 40 and turn over cam 52 are secured upon a sleeve 73 with a pulley 74 by the key 75, and the sleeve, which is provided with a head 76, is secured to the crank shaft by the key 77. The timing of the cams necessarily varies with the length of the blank, and to provide for such variation, with the least possible labor, and to insure a positive retiming, I have provided an additional key-way 78 in the bore of the sleeve 73, and an additional key-way 79 in the shaft 3. To change the position of the 85 cams and the timing thereof which results therefrom, it is simply necessary to withdraw the key 77 from the position shown in the drawings (Figs. 7 and 9) and replace it in the key-way formed by the junction of the key-ways 78 and 79. This, it will be noted, does not affect the relative positions of the cams themselves, which are permanently secured upon the sleeve 73 by the key 75.

Fixed to the bed by the bolts 60, is the die block 61, to which the die holder 62, having the die 64 therein, is securely held by the clamp 63. The die is preferably cylindrical in form for economy in manufacture, and the opening 65 therethrough is the same shape in cross section as that of the finished head of the bolt to be operated upon.

In mechanism of this character heretofore 120 made, no means have been provided for insuring the alinement of the blank with the opening in the die, which frequently resulted in an imperfect operation of the machine. The fingers in the old form would sometimes rotate the bolt slightly, as their engagement was being broken with the bolt, or the jar of the machine, or for other reasons, the bolt would be thrown slightly out of alinement, the result being, that a corner of 125 130

the bolt head would be trimmed off, ruining the bolt and placing an excessive strain upon both the punch and die. I have eliminated this difficulty by providing means for 5 positively alining the blank with the die, which means comprise, the guide plates 66, having arms 67 integral therewith projecting laterally upon one side thereof with an angular inner face 68 near their outer ends. 10 These guide plates are moved by the springs 70 toward the center of the die until the shoulders 69 thereon contact with the die, in which position, the inner edge of the plates are in register with the opposite edges of 15 the opening (square) through the die, as shown in Figs. 4 and 6. Outward movement of the guide plates 66 is limited by the contact of the shoulders 71 with the caps 72, within which the said guide blocks are slidably mounted. The heads of the blanks, as 20 they approach the punch, contact with the angular faces 68 upon the guide plates and rotate within the fingers until they register with the opening in the punch. This mechanism 25 positively alines the blanks and brings them into their true relative position with the die without depending upon chance.

It is desirable, for some classes of work, to hold the die so that it may be shifted, 30 thereby insuring its positive alinement with the punch. I have devised such means, and have illustrated the same in Figs. 12 and 13 of the drawings. In this embodiment of my invention, the bed 1 is provided with openings 35 85 of larger diameter than the bolts 60, and the die block 61 rests upon the end of a lock screw 86 that is threaded through a lug 87 integral with the bed. An adjusting screw 88 passes entirely through the lock 40 screw 86 and is threaded into said die block. The die 64 is mounted in the holder 89, having an ear 90 at one end, in which the screw 91 is rotatably mounted, but held against endwise movement therein by the collars 92. 45 A vertical adjustment is given the die 64 by first loosening the bolts 60, then the screw 88, and afterward bringing it to its true position by rotation of the lock screw 86. Gravity at all times holds the die block 50 against the end of the lock screw. After the die has been moved to its vertical position, the same is maintained therein by first tightening the screw 88 and then the bolts 60. A horizontal adjustment of the die is 55 obtained by releasing the hold of the clamp 68 upon the die holder 89 and then shifting the die holder by the rotation of the screw 91, that is threaded into the die block 61. The mechanism for alining the position of 60 the bolt head with reference to the opening in the die, heretofore described, is applicable also to the modified form of die block shown in Figs. 12 and 13, although not shown therein.

65 In operation, the blanks move through the

delivery chute until they contact with the angle plate 13, shown by broken lines in Fig. 11. The fingers, in what is known as the zero position, that is, adjacent to the face of the sleeve 33, in the relative position about 70 the axis of said sleeve, shown by broken lines in Fig. 5, move therefrom toward the chute and pass through the recess 19 in the reversible block 17, and engage the shank of the blank, the finger tips passing over the blank, 75 which enters the notch 39, as above described. The fingers carrying the blank now move away from the delivery chute, the plugs 14 yielding sufficiently to allow the blank to pass thereby, until the blank is entirely free from the chute, when the sleeve 80 and the fingers are rotated to the position substantially shown by full lines in Fig. 5, wherein the axis of the bolt lies substantially parallel with the axis of the punch and die. 85 The fingers now move toward the punch and die carrying the blank therewith until its axis is coincident with that of both the punch and die, the position of the head of the blank in relation to the punch, being rectified during the last portion of this movement by the mechanism above described. At this time, the punch moving toward the die encircles the blank, and when it has a sufficient hold upon it, the fingers are withdrawn. 90 The punch continues its movement and forces the head of the blank into the die where it is trimmed as desired. During the return movement of the punch, the blank is ejected from the die through a knockout mechanism that is usual in this type of machine, and consists essentially of a knockout pin 80, which is acted upon by a lever 81 that is pivotally secured by a pin 82 to the bed 1 and actuated through a rod 83 connected therewith, and to the gate. After 95 leaving the die the blanks drop into a receptacle conveniently arranged to receive them.

There are minor changes and alterations 110 that can be made within my invention, aside from those herein suggested, and I would therefore have it understood, that I do not limit myself to the exact construction herein shown and described, but claim all that falls 115 fairly within the spirit and scope of my invention as set forth in the appended claims.

Having described my invention, what I 120 claim as new, and desire to secure by Letters Patent, is:—

1. In combination with a blank support and operating tools; a feed mechanism for transferring blanks from said blank support to said operating tools, comprising carrying fingers, reciprocating mechanism, to 125 which said fingers are attached, and means for operating said fingers, whereby the initial movement thereof, after said fingers have engaged said blank, is at an angle to the direction of movement of the blanks 130.

within the blank support, and the final movement of said fingers with said blank is in a path substantially parallel with said initial movement, but in the opposite direction.

2. In a device of the character described, the combination with a die; of a delivery chute; means for transferring blanks from said delivery chute to said punch; and means for insuring the positive alinement of said blanks with the opening in said die.

3. In a device of the character described, the combination with a die; of a delivery chute; means for transferring blanks from said delivery chute to said die; and means for positively alining the heads of said blanks with the opening in said die, said means acting upon said blank during the transfer movement thereof from the delivery chute.

4. In a device of the character described, the combination with a die; of a blank support; means for transferring blanks with angular heads from said blank support to said die; and means, in the path traveled by said blank to the die, for rotating said blank about its axis while engaged by said transfer means when the angular sides of the head thereof are not parallel with the angular sides of the opening in the die, so that said head will register with the opening in said die, at the completion of said transfer movement.

5. The combination with a die; of guide plates movably mounted adjacent thereto, having faces thereon that lie opposite each other and in line with opposite faces of the opening in said die, said parallel faces flaring outwardly away from said die and forming a throat therebetween wider than the space between the opposite faces of the opening in said die.

6. The combination with a die; of companion guide plates movably mounted upon opposite sides of said die, having lateral arms thereon that are straight for a portion of their length and flare outwardly at one end thereof; spring means for moving said plates in one direction; and means, as a stop for limiting the movement of said guide plates when the said straight portions thereof are in line with one side of the opening in said die.

7. In a device of the character described, the combination with a die; of a delivery chute; transfer fingers for carrying blanks from said delivery chute to said die, said fingers grasping the shank of the blank while in said delivery chute and moving the same therefrom in a path at substantially a right angle to the movement of the blanks in said delivery chute; means for rotating said fingers with the blank therein substantially 90° ; and means for moving said fingers after said rotation through a path sub-

stantially parallel with that prior to said rotation but in the opposite direction, to a point where the blanks are brought into register with the opening in said die.

8. In a device of the character described, the combination with a die; of a delivery chute; and means for transferring blanks from said delivery chute to said die, said means comprising a sleeve held against rotation except about its axis, a spindle held against rotation within said sleeve, fingers connected with said spindle, means for imparting a reciprocatory movement to said spindle, and means for imparting a rotary movement to said sleeve about its axis.

9. In a device of the character described, the combination with a die; of a delivery chute; and means for transferring blanks from said delivery chute to said die, said means comprising a sleeve held against rotation except about its axis, means for imparting a partial rotation to said sleeve at predetermined periods about its axis, a spindle held against rotation within said sleeve, carrying fingers connected with said spindle, and means for imparting a plurality of reciprocatory movements of varying lengths to said spindle.

10. In a device of the character described, the combination with a die; of a delivery chute; a sleeve; a spindle within said sleeve; means for holding said spindle against rotation within said sleeve; a head block connected with said spindle; fingers connected with said head block; cam actuated means for imparting a rotary movement to said sleeve and through it to said fingers; and cam-actuated means for imparting a reciprocatory movement to said spindle within said sleeve.

11. In a device of the character described, the combination with a die; of a delivery chute; a sleeve; a spindle within said sleeve; means for holding said spindle against rotation within said sleeve; a head block connected with said spindle; fingers connected with said head block; a rotary shaft; cam actuated means for imparting a rotary movement to said sleeve and through it to said fingers; cam actuated means for imparting a reciprocatory movement to said spindle within said sleeve; and means for separably connecting said cams to said shaft, whereby they may be secured in various positions about the axis thereof and at the same time occupy the same relative positions with each other.

12. In a device of the character described, the combination with a die; of a delivery chute; a sleeve; a spindle within said sleeve; means for holding said spindle against rotation within said sleeve; a head block connected with said spindle; fingers connected with said head block; a rotary shaft; cam actuated means for imparting a rotary

- movement to said sleeve and through it to said fingers; cam actuated means for imparting a reciprocatory movement to said spindle within said sleeve; a sleeve to which said cams are secured; and means for securing said sleeve in various positions about the axis of said shaft without affecting the relative positions of said cams upon said sleeve.
- 10 13. The combination with a rigid part; of a die block; and means for adjustably securing said die block to said rigid part, comprising one or more bolts passing through openings in said rigid part of greater diameter than said bolts, a lock screw threaded in said rigid part and abutting against said die block, and an adjusting screw threaded into said die block for holding said die block against said lock screw.
- 20 14. The combination with a rigid part; of a die block; means for adjustably securing said die block to said rigid part, comprising one or more bolts passing through openings in said rigid part of greater diameter than said bolts, a lock screw threaded in said rigid part and abutting against said die block, and an adjusting screw threaded into said die block for holding said die block against said lock screw; a die holder; and means for adjustably securing said die holder in said die block.
- 25 15. In a device having a blank support and operating tools, the combination therewith of a feed mechanism having fingers, mechanism for advancing the fingers in substantially a right line toward the blank support to engage a blank, for withdrawing the fingers in substantially a right line with a blank, for oscillating the fingers so as to turn the blank substantially 90°, and for carrying the fingers with the blank in substantially a right line, after having been turned 90°, said oscillation taking place at the termination of the withdrawing movement and before the commencement of the succeeding right line movement.
- 30 16. In a device having a blank support and operating tools, the combination therewith of a feed mechanism having fingers, mechanism for advancing the fingers in substantially a right line toward the blank support to engage a blank, for withdrawing the fingers in substantially a right line with a blank, for oscillating the fingers so as to turn the blank substantially 90°, and for carrying the fingers with the blank in substantially a right line, after having been turned 90°, said oscillation taking place at the termination of the withdrawing movement and before the commencement of the succeeding right line movement.
- 35 17. In a device having a blank support and operating tools, the combination therewith of a feed mechanism having fingers, mechanism for advancing the fingers in substantially a right line toward the blank support to engage a blank, for withdrawing the fingers in substantially a right line with a blank, for oscillating the fingers so as to turn the blank substantially 90°, and for carrying the fingers with the blank in substantially a right line, after having been turned 90°, said oscillation taking place at the termination of the withdrawing movement and before the commencement of the succeeding right line movement.
- 40 18. In a device having a blank support and operating tools, the combination therewith of a feed mechanism having fingers, mechanism for advancing the fingers in substantially a right line toward the blank support to engage a blank, for withdrawing the fingers in substantially a right line with a blank, for oscillating the fingers so as to turn the blank substantially 90°, and for carrying the fingers with the blank in substantially a right line, after having been turned 90°, said oscillation taking place at the termination of the withdrawing movement and before the commencement of the succeeding right line movement.
- 45 19. In a device having a blank support and operating tools, the combination therewith of a feed mechanism having fingers, mechanism for advancing the fingers in substantially a right line toward the blank support to engage a blank, for withdrawing the fingers in substantially a right line with a blank, for oscillating the fingers so as to turn the blank substantially 90°, and for carrying the fingers with the blank in substantially a right line, after having been turned 90°, said oscillation taking place at the termination of the withdrawing movement and before the commencement of the succeeding right line movement.
- 50 20. In a device having a blank support and operating tools, the combination therewith of a feed mechanism having fingers, mechanism for advancing the fingers in substantially a right line toward the blank support to engage a blank, for withdrawing the fingers in substantially a right line with a blank, for oscillating the fingers so as to turn the blank substantially 90°, and for carrying the fingers with the blank in substantially a right line, after having been turned 90°, said oscillation taking place at the termination of the withdrawing movement and before the commencement of the succeeding right line movement.
- 55 21. In a device having a blank support and operating tools, the combination therewith of a feed mechanism having fingers, mechanism for advancing the fingers in substantially a right line toward the blank support to engage a blank, for withdrawing the fingers in substantially a right line with a blank, for oscillating the fingers so as to turn the blank substantially 90°, and for carrying the fingers with the blank in substantially a right line, after having been turned 90°, said oscillation taking place at the termination of the withdrawing movement and before the commencement of the succeeding right line movement.
- 60 22. In a device having a blank support and operating tools, the combination therewith of a feed mechanism having fingers, mechanism for advancing the fingers in substantially a right line toward the blank support to engage a blank, for withdrawing the fingers in substantially a right line with a blank, for oscillating the fingers so as to turn the blank substantially 90°, and for carrying the fingers with the blank in substantially a right line, after having been turned 90°, said oscillation taking place at the termination of the withdrawing movement and before the commencement of the succeeding right line movement.

In testimony whereof I affix my signature in presence of two witnesses.

RICHARD LESTER WILCOX.
